UNITED STATES PATENT OFFICE.

LOUIS R. HORTON, OF PROVIDENCE, RHODE ISLAND, ASSIGNOR TO THE J. B.
& S. M. KNOWLES COMPANY, OF SAME PLACE.

DESIGN FOR A SPOON.

SPECIFICATION forming part of Design No. 21,461, dated April 12, 1892.

Application filed March 8, 1892. Serial No. 424,229. Term of patent 7 years.

To all whom it may concern:

Be it known that I, LOUIS R. HORTON, a citizen of the United States, residing at Providence, in the county of Providence and State 5 of Rhode Island, have invented and produced a new and original Design for Spoons, of which the following is a specification, reference being had to the accompanying drawings, forming part thereof.

Figure 1 is an obverse view of the spoon and handle thereof. Fig. 2 is a reverse view of the handle.

The leading features of my design for spoons and the handles thereof consist in the symmetrical wave-like outline of the bowl, which approaches a circle in shape, the wave-like ribs formed on the inner surface of the bowl and the scroll ornaments extending around a portion of the upper part of the bowl, and small scrolls issuant from the smallest rib, together with the gradual enlargement of the handle, the slight contraction of the same near the top, a foliated scroll-border extending around the obverse surface of the handle, and a scrolled border around the reverse thereof and uniting at the upper end of the handle in a foliated ornament.

Numeral 3 in the drawings designates the bowl of the spoon, which approaches an irregular circle in outline and has the indentations 4, 5, and 6, the curved lines joining these giving a wave-like effect. The parallel ribs or corrugations 7, 8, and 9 are formed on the inner surface of the bowl, that marked 9 being crossed near the lower portion of the bowl

by the tapering cross-corrugation 10. From the corrugation 7 extend the scrolls 11 11, while around the upper portion of a side of the bowl is a scrolled ornament 12.

The outline of the handle 13 of the spoon 40 gradually widens from the junction with the bowl 3 until it reaches the points 14 14, when it curves inward, then slightly outward and inward to form the edges of the scrolls 15 15, and then outward and inward in a succession 45 of small curves to accentuate the outline of the foliated scroll-work 16 at the upper end of the handle, the scrolls 15 being connected with the ornament 16 by a series of slightly-foliated scrolls. From the scrolls 15 15 there 50 extend down onto the narrow portion of the handle the scrolled borders 17 17.

The reverse surface of the handle 13 is furnished with a beaded border 18, having scrolled ends and overlapped by the scroll ornaments 55 19 19. At the upper contracted portion of the handle these borders are separated by the ornaments 20 20, from whence the beaded border curves around, following the outline of this portion of the handle, and are united 60 by the foliated ornament 21, formed on said reverse surface of the handle.

What I claim is—

The design for a spoon, as herein shown and described.

LOUIS R. HORTON.
